UNITED STATES PATENT OFFICE.

HOWARD R. SARGENT AND THEODORE A. KOCH, OF SCHENECTADY, NEW YORK,
ASSIGNORS TO GENERAL ELECTRIC COMPANY, A CORPORATION OF NEW
YORK.

SOCKET OR RECEPTACLE.

1,334,799.

Specification of Letters Patent. Patented Mar. 23, 1920.

Application filed January 27, 1914. Serial No. 814,841.

To all whom it may concern:

Be it known that we, HOWARD R. SARGENT, a citizen of the United States, residing at Schenectady, county of Schenectady, State of New York, and THEODORE A. KOCH, a citizen of the United States, residing at Schenectady, county of Schenectady, State of New York, have invented certain new and useful Improvements in Sockets or Receptacles, of which the following is a specification.

Our invention relates to sockets and receptacles for incandescent electric lamps and the like, and its object is to prevent theft or unauthorized interchanging, removal, or insertion of such lamps. Various other advantages obtainable in connection with the invention will hereinafter become apparent,—such as simplicity, strength, durability, ruggedness, reliability, good appearance, and facility and cheapness of manufacture, for example,—while the scope of the invention will be indicated in our claims.

In accordance with our invention, we so construct a socket in which a lamp is inserted or from which it is removed by a turning movement that ordinarily some lamp engaging part of the socket structure with reference to which the lamp must turn during insertion or removal will itself turn more or less freely, but that such part can be prevented from doing so by an authorized person. We have hereinafter shown and described socket structures especially intended for lamps or other devices having terminals or bases of the so-called Edison screw type in which the screw shell that ordinarily forms the principal lamp engaging part of the Edison type of socket is rotatably mounted and has engagement means additional to its threads for coacting with a special member or key to prevent it from turning when a lamp is to be inserted or removed. While, however, these structures are the best for the purposes of the invention at present known to us, and while the invention extends to these particular forms of device and to their specific features and details and combinations and arrangements of parts, yet the invention is not confined thereto, but can be otherwise carried out and embodied.

In the accompanying drawings, Figure 1 is a side view of a socket or receptacle of

the switchless type suitable for mounting on a wall or ceiling, the same being constructed in accordance with our invention.

Fig. 2 is a similar view with the structure turned to an angle of 90° from the position shown in Fig. 1, certain outer parts being in section.

Fig. 3 is a vertical mid-section through the device and most of its parts on a plane of section different from that of Fig. 2.

Fig. 4 is a view of certain parts as seen when viewed in the direction of the arrows from a plane of section corresponding to the line 4—4 in Fig. 3, the inclosing or incasing parts being removed.

Fig. 5 is a plan view of a part associated with the screw shell.

Fig. 6 is a fragmentary detail similar to Fig. 2 illustrating the locking of the socket for removal or insertion of a lamp.

Figs. 7 and 8 are fragmentary detail views illustrating certain features of construction.

Fig. 9 is a side view of the principal interior parts of a key type of socket constructed in accordance with our invention.

Fig. 10 is a similar view from the left-hand side of Fig. 9, certain parts being in section.

Fig. 11 is a fragmentary view similar to Fig. 10 showing certain switch parts in a different position.

Fig. 12 is a plan view of the switch mechanism with the parts in the positions shown in Fig. 10, the upper part of the inclosing structure being removed.

Fig. 13 is a perspective view of certain parts of the switch mechanism by themselves.

From Figs. 1, 2 and 3 it will be seen that the device illustrated comprises a base structure 1 that carries various conductive parts; a rotatable screw shell contact and engagement part 2 mounted on said base; another contact part 3—such as is commonly known as a "center contact"—exposed within the screw shell proper, and an outer inclosing shell or casing 4 with an insulative lining 5 of fiber or other material. The insulation of the parts carried by the base structure 1 can best be secured by making it in a single piece of insulating material such as porcelain or bisque, and the screw shell portion of the part 2 and the outside casing 4 can best be made of brass or other sheet metal, as

usual. These parts and their relative arrangement are in a general way quite similar to those of various sockets and receptacles now in ordinary use, so that description of many of their features may be dispensed with. Preferably the lining 5 protrudes somewhat beyond the edge of the casing shell 4, and the screw shell proper has its edge well back from the edges of the casing shell 4 and the lining 5 and fits the lining loosely. This arrangement leaves the screw shell free to turn and at the same time makes it impossible to insert a knife blade between the lamp and the walls of the socket far enough to jam the screw shell.

Referring, now, to Figs. 3 and 4, it will be seen that the current connection to the center contact part 3 comprises a bent strip 6 of sheet metal one end of which has in it a screw for the attachment of a current supply wire and the other end of which lies in a groove in the lower surface of the base 1 and carries a downwardly extending hollow internally threaded stud 7 firmly secured in a hole therein and arranged so as to be substantially coaxial with the screw shell part 2. The parts 6 and 7 are secured in position by a screw 8 that extends down from the upper side of the base 1 through a central hole therein and engages the threads in the stud 7. The center contact part 3 is mounted directly on the stud 7,—preferably loosely enough to turn freely,—and is kept from shifting lengthwise of the stud 7 by a shoulder formed by an enlarged upper portion of the stud and by a washer 9 that lies in a depression in the lower side of said part 3 and is secured on the reduced lowermost portion of the stud by expansion or beading over of the extreme end thereof. A disk part 10 of fiber or other insulating material having a central opening through which extend parts 3 and 7 fits rather loosely in the bottom of the screw shell proper above the enlargement or flange at the lower end of the former which forms its engagement portion and insulates the center contact 3 therefrom and keeps the parts approximately coaxial. Thus the stud 7 serves as a means for pivotally securing the contact 3 and the part 10 with which it is associated to the base 1, besides forming part of the current connection to the former.

The screw shell portion of the part 2 has in its upper end or bottom 11 a central opening through which the part 3 and the stud 7 extend without contact with this shell, there being an upstanding flange or collar 12 at the edge of this central opening. The engagement means of the screw shell part 2 whereby it can be prevented from turning comprises a plurality of shoulders or projections 13 formed by the sides of notch or groove-like recesses 14 at the edge of a circular disk 15 so secured to the upper end or

bottom 11 of the screw shell proper that relative turning of the shell and the disk is prevented. As shown in Figs. 3 and 5, the disk 15 has a central opening that fits over the flange 12 of the shell proper and also a plurality of notches 16 that receive punched up portions 17 of the shell bottom 11 (Fig. 3), and the upper end of the flange 12 is expanded or beaded over on an annular metallic member or washer 18 at the upper side of said disk. The turned over edge of the flange 12 lying almost against the flat lower surface of the base 1 and the part 10 fitting in and resting against the bottom of the shell proper, the screw shell contact part 2 as a whole is pivotally secured to the base by the stud 7, so that while it is quite free to turn it is at the same time securely held and completely insulated. The rigidity and fixity of the center contact 3 in an axial direction with reference to the shell part proper tends to insure a tight bottoming of the lamp against it when screwed in, and the disk part 10 can readily be made strong enough to prevent injury from screwing in of the lamp too tight.

It is preferable that the key member engaging shoulders 13 should be insulated from the lamp engaging threaded shell proper, in order that the key member may not by any possibility become electrified or cause a short circuit. This can be most easily accomplished by making the whole disk 15 of indurated fiber or other suitable insulating material and utilizing the annular part 18 as a contact for making electrical connection with the shell proper without interference with its rotation. As shown in Figs. 2, 3 and 4, the connection is effected by means of a curved contact strip 19 of cold rolled copper or other resilient metal arranged in an appropriately shaped recess in the lower surface of the base 1 with its ends bent upward so as to rub against the annular contact means 18. The contact 19 is clamped in place beneath an irregularly bent strip 20 of sheet metal corresponding to the strip 6 that is secured to the base 1 by a screw 21 in very much the same way. Besides carrying current, the spring strip 19 insures against rattling of the parts 2, 3 and 10 on the stud 7 or against the base 1.

We have already referred to the use of a key member for locking the screw shell part 2 against turning when a lamp is to be inserted or removed. In the device shown, the locking is very simply effected by direct engagement of the key 22 itself with one of the shoulders 13 of the recessed disk 15 (see Figs. 2 and 6), without the intervention of any bolt, catch, or other intermediate mechanism, while security is assured by so locating and arranging the key-hole means of the casing 4 with reference to the engagement means 13 and 15 that

After initial insertion as far as possible the key 22 must be otherwise moved to bring it into position to engage said means 13, means being preferably provided to hold the key against movement in either direction by the engagement means 13 when thus associated with the casing 4. This can conveniently be accomplished by a barrier that the entering key must pass at an angle to its position when engaged,—so that the key must be turned after passing the same,—in conjunction with means for preventing turning of the key when engaged, or even when about to engage.

As shown in Figs. 1, 2, 6 and 8, there is an irregular key-hole slot 23 in a flattened portion 24 at one side of the main wall of the casing 4 arranged so that the key enters it transversely with reference to the axis of rotation of the screw shell part 2 and when in it is in its proper engaging position, and there is a similar key-hole slot 25 in an outer barrier wall 26 formed by the bottom of a sheet metal cap 27 secured to the casing 4 by tongue-like extensions 28 of its own walls that pass through holes in the wall 24 and are bent over, and a barrel or shield part 29 with a longitudinal groove for the flat stem 30 of the sheet metal key 22 is mounted between the walls 24 and 26 with its own reduced ends in holes at the approximately superposed corresponding ends of the slots 23 and 25 (Figs. 7 and 8). The slots 23 and 25 are arranged at a 90° angle to one another, so that the barrier wall 26 necessitates turning of the key after its initial insertion, and the cylindrical wall of the cap 27 is so located with reference to the outer ends of the slots 23 and 25 as to arrest the web 31 of the key 22 in the proper position for entering the former or being withdrawn through the latter. A shoulder 32 on the key handle prevents the web 31 from ever passing beyond the wall 24 when entering the inner key-hole slot 23 and so insures that the key 22 shall be kept from turning by its edges. If it happens that no notch 14 is opposite the inner key-hole 23 when the key 22 comes into engaging position, the inward movement of the key will be stopped by the edge of the disk 15 (Fig. 2) till the latter is suitably turned by manipulation of the lamp (Fig. 6) or of the screw shell part 2 itself.

The key-hole means shown and just described is very simple and cheap to manufacture while at the same time quite secure against the thief. The difficulties of theft can be considerably increased by providing wards within the cap 27 without otherwise increasing the cost since even rather complicated key forms can be punched and bent from sheet metal at a single operation.

Referring, now, to the switch socket construction illustrated in Figs. 9 to 13, it will

be seen that there is a base structure 101 that carries the switch mechanism and various other conductive parts, a screw shell contact and engagement part 102 rotatively mounted on said base 101, and a center contact part 103, just as in the receptacle already described. The contact parts 102 and 103 are like the corresponding parts 2 and 3 of the receptacle already described, and the parts 109, 110, 119, 120, etc., and their relations to one another and to the base structure 101 are like the parts 9, 10, 19, 20, etc., (Figs. 2, 3 and 4). The stud 107 that serves for the securing of various parts and as a portion of the current connection to the center contact 103 differs from the stud 7 only in being solid at its upper end where it is riveted into the flat plate or strip 106 and in being without internal threads.

The base structure 101 is in lower and upper parts 140 and 141 having recesses in their abutting faces which form a substantially closed chamber 142 for the switch mechanism whereby electrical connection to the center contact 103 is made and broken. The part 106 that carries the stud 107 and hence the center contact 103 is secured in any suitable way to the lower side of the lower part 140 with its own upper side exposed in the switch chamber 142 where it may be directly engaged by the movable contact member 143 of the switch mechanism. The switch mechanism comprises a sort of U-shaped frame structure 144 having a lug 145 by means of which it is screwed to the upper base part 141, a pair of guide portions 146 having elongated holes 147 that afford bearings for the operating shaft 148 on which is the handle 143, and a screw for the attachment of a current supply conductor. The movable contact 143 consists of an oblong rectangular piece of metal mounted between the guide parts 146 and having an elongated hole 151 with the sides of which engage projections on the portion of the shaft 148 extending therethrough. A disk 152 having slots for the guides 146 is arranged above the contact member 143 and is continually urged downward by a spiral spring 153. The spring 153 coacts with the flat surfaces of the parts 106 and 142 and of the contact member 143 to give the switch a snap action that insures a quick break, and it also insures a good electrical connection from the part 144 to the part 106 when the switch is in the "on" position shown in Fig. 11.

It will readily be seen that with the construction and arrangement illustrated the electrical connections to the screw shell and to the center contact 103 do not in the least interfere with the rotation of the screw shell contact part 102, so that it is just as much impossible to remove a lamp from the socket when the current is on as when it is off.

What we claim as new and desire to secure by Letters Patent of the United States, is:—

1. A socket or receptacle for incandescent lamps and the like comprising a rotatively mounted part having engagement means adapted to be brought into engagement with a lamp by relative turning of the lamp and said part and having additional engagement means, and a casing inclosing said part and having key-hole means for the introduction of a key to engage said additional engagement means and prevent turning of said part, said key-hole means being so located and arranged with reference to said additional engagement means that after initial insertion as far as possible the key must be otherwise moved therein to bring it into position to engage said additional engagement means, and there being means for holding 20 the key against movement in either direction by said additional engagement means when in such position.
2. A socket or receptacle for incandescent lamps and the like comprising a rotatively mounted part having engagement means adapted to be brought into engagement with a lamp by relative turning of the lamp and said part and having additional engagement means, and a casing inclosing said part and having key-hole means for the introduction of a key to engage said additional engagement means, said key-hole means comprising a barrier which the entering key must pass at an angle to its engaging position, so that 35 the key must be turned after passing the same, and also comprising means for preventing turning of the key when engaged.
3. A socket or receptacle for incandescent lamps and the like comprising a rotatively mounted part having engagement means adapted to be brought into engagement with the lamp by the relative turning of the lamp and said part and having additional engagement means, and a casing inclosing said part 40 and having key-hole means for the introduction of a key to engage said additional engagement means and prevent turning of said part, said key-hole means comprising inner and outer walls with key-holes therein so located and arranged that after insertion of the key in the outer key-hole a portion thereof must be moved between the walls to allow the key to enter the inner key-hole and bring it in position to engage said additional 55 engagement means.
4. A socket or receptacle for incandescent lamps and the like comprising a rotatively mounted part having engagement means adapted to be brought into engagement with a lamp by relative turning of the lamp and said part and having additional engagement means, and a casing inclosing said part and having at its side key-hole means for the introduction of a webbed key transversely with reference to the axis of said 60
5. A socket or receptacle for incandescent lamps and the like comprising a rotatively mounted part to engage said additional engagement means and prevent turning of the said part, said key-hole means comprising inner and outer walls with key-holes therein arranged at an angle to one another, so that after insertion of the key in the outer one it must be turned therein with its web between said walls to permit it to enter the inner one, said inner key-hole being so located with reference to said additional engagement means that as the key enters said inner wall its web will come into position to engage said additional engagement means and that the edge of said inner wall will prevent turning movement 75 of the key.
6. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 80 secured to said casing over said first-mentioned key-hole, there being between the bottom of said cap and the walls of said casing space for movement of the web of the key.
7. A socket or receptacle comprising a base, a screw shell contact part itself comprising a screw shell proper and a disk of insulating material secured to the end of said shell and having a central opening and recesses at its edge, a part of insulating material fitting loosely in said screw shell proper of larger diameter than said opening, a center contact associated with said part and exposed in said screw shell, means 85 extending through said opening whereby 90
8. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 95 secured to said casing over said first-mentioned key-hole, there being between the bottom of said cap and the walls of said casing space for movement of the web of the key.
9. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 100 secured to said casing over said first-mentioned key-hole, there being between the bottom of said cap and the walls of said casing space for movement of the web of the key.
10. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 105 secured to said casing over said first-mentioned key-hole, there being between the bottom of said cap and the walls of said casing space for movement of the web of the key.
11. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 110 secured to said casing over said first-mentioned key-hole, there being between the bottom of said cap and the walls of said casing space for movement of the web of the key.
12. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 115 secured to said casing over said first-mentioned key-hole, there being between the bottom of said cap and the walls of said casing space for movement of the web of the key.
13. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 120 secured to said casing over said first-mentioned key-hole, there being between the bottom of said cap and the walls of said casing space for movement of the web of the key.
14. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 125 secured to said casing over said first-mentioned key-hole, there being between the bottom of said cap and the walls of said casing space for movement of the web of the key.
15. A screw shell contact part adapted to be rotatably mounted upon the base of a socket or receptacle comprising a screw shell proper having in its bottom an opening with an upstanding flange at its edge and a disk of insulating material having an opening through which said flange extends and secured against the bottom of said screw shell proper by an expanded portion of said flange, said shell and said disk 130 secured to said casing over said first-mentioned key-hole, there being between the bottom of said cap and the walls of said casing space for movement of the web of the key.

said insulating part and hence said screw shell contact part are pivotally secured to said base, said means serving as an electrical connection for said center contact, means carried by said base for making electrical connection with said screw shell without interference with its rotation, and a casing inclosing said screw shell and having an opening for the insertion of a key for locking 10 said screw shell contact part against turning by means of said recessed disk.

8. A socket or receptacle comprising a base, a screw shell contact part, a center contact part associated therewith and exposed in the screw shell, said screw shell contact part being rotatively mounted but having engagement means for coacting with corresponding engagement means associated 15

with a stationary socket part to prevent it from rotating, means carried by said base 20 for making uniform sliding and electrical connection with said screw shell without interference with its rotation, switch means carried by said base for making and breaking electrical connection with said center 25 contact part also without interference with the rotation of the screw shell, and a casing inclosing said base and said screw shell.

In witness whereof, we have hereunto set our hands this 26th day of January, 1914. 30

HOWARD R. SARGENT.
THEODORE A. KOCH.
